REEL FLANGE

George F. Lyman, South Hadley, Mass., and Gregory Mathus, West Hartford, Conn., assignors to The Morningstar Corporation, Cambridge, Mass., a corporation of Massachusetts

Filed Oct. 20, 1964, Ser. No. 82,243

Term of patent 14 years

(Cl. D61—1)

FIG.1

FIG.2

FIG.3

FIG.4

FIG. 1 is a top plan view of a reel flange, showing our new design;

FIG. 2 is a cross-sectional view thereof taken on line 2—2 of FIG. 1, a reel hub and second reel flange being indicated in broken lines for illustrative purposes only;

FIG. 3 is an enlarged fragmentary cross-sectional view thereof taken on line 3—3 of FIG. 1; and

FIG. 4 is a top plan view of a modified embodiment of the reel flange shown in FIG. 1.

Stippling and cross-hatching are employed to indicate contrast of surface texture and color.

This application is a continuation-in-part of our prior copending application No. D-79,995, filed May 15, 1964, and now abandoned.

We claim:

The ornamental design for a reel flange, as shown and described.
